Delaware

Application December 19, 1947, Serial No. 792,797

11 Claims. (Cl. 250—175)

1

This invention relates to television pick-up tubes and in particular to a novel gun structure for use in such tubes.

One type of television pick-up tube has an electron gun for forming an electron beam which can be scanned across a target transverse to the axis of the electron gun. The beam is one of relatively low velocity in which the electrons are speeded up to 200-300 volt velocity and then deaccelerated to practically zero velocity. The target has a glass surface across which the beam is scanned magnetically. The beam striking the target surface reduces its potential to an equilibrium value determined by the potential of the cathode of the electron gun. At this equilibrium potential, the electron beam is repelled by the target surface to form a return beam which is accelerated back toward the gun cathode. A charge pattern of positive areas is established upon the target surface corresponding to a light image focused on the tube. When the scanning electron beam reaches an elemental positive area of the target, it will lose electrons to discharge the positive area to equilibrium potential at which point the remainder of the beam is repelled. In this manner, an electron beam of uniform density scans the target while a non-uniform or modulated beam is returned to the cathode end of the tube where it is collected and amplified as the output signal.

The modulated return beam is picked up and amplified by a plural stage multiplier in which the end of an accelerating anode cylinder serves as the first multiplier stage. Secondary electrons emitted by the action of the return beam upon the surface of the first multiplier stage pass into an electrostatic field which pulls them over to the second multiplier stage where they strike to produce a greater number of new secondary electrons. These additional electrons in turn pass on to succeeding stages giving rise at each stage to a greater number of secondaries which are finally collected as the video signal of the tube.

Due to the introduction of several factors, the return beam will scan the surface of the first multiplier stage over an appreciable area. To prevent the production by the multiplier section of a non-uniform brightness of the video signal of the tube, the second stage must collect secondaries uniformly from all parts of the scanned area of the first stage as well as provide the same multiplication for electrons coming from the scanned area of the first stage. In orthicon pick-up tubes of the type described above it has been difficult to consistently produce uniform collection by the second multiplier stage of secondary electrons

2

emitted from the first stage, which would result in a video signal giving a uniformly bright picture.

It is, therefore, an object of my invention to provide an improved television pick-up tube.

It is also an object of my invention to provide an improved structure for a multiplier section of a television pick-up tube providing an improved video signal.

10 It is a further object of my invention to provide an improved structure for the multiplier section of a television pick-up tube which will result in uniform collection of the signal between the first and second multiplier stages.

15 The novel features which I believe to be characteristic of my invention are set forth with particularity in the appended claims, but the invention itself will best be understood by reference to the following description taken in connection with 20 the accompanying drawing, in which:

Figure 1 is a longitudinal cross-sectional view of a television pickup tube incorporating the details of my invention; and

25 Figure 2 is an enlarged longitudinal view with parts broken away to show details of the multiplier section of the television pickup tube of Figure 1.

Figures 1 and 2 disclose a television pickup tube for transmitting high frequency signals corresponding to an external scene optically viewed by the tube. The tube shown in Figures 1 and 2 is one form of a type of television pickup tube which utilizes an electron image of the scene viewed by the tube and a low velocity scanning beam of electrons for providing the video signal. In greater detail, the tube consists of a glass envelope 10 of tubular shape having an enlarged section 11 at one end. The enlarged section 11 is closed by a flat glass face plate 12 having deposited on the inner surface thereof a transparent photoelectric film 14 which is sensitized in a well known manner to provide an emission of photoelectrons when an exterior scene is focused optically upon the surface of the face plate 12. Mounted within the enlarged envelope portion 11 is a glass target 22. In one embodiment of my invention, for example, the photosensitive electrode 14 is maintained, during tube operation, at around 400 volts negative relative to the target electrode 22. During normal tube operation, a direct current passed through a solenoid coil 16 provides a uniform magnetic field with lines of force substantially parallel to the axis of the tube to direct the photoelectrons in parallel paths between the photocathode 14 and target 22. An

electrode 18 of tubular form surrounds the paths of the photoemission from electrode 14 between the photocathode 14 and target 22. The tubular electrode 18 is maintained, for example, at around 300 volts positive relative to the photocathode 14 and acts as an accelerating electrode for the photoelectrons passing between the photocathode 14 and the target 22. A fine mesh collector screen 20 is closely spaced from target 22 and is maintained, for example, at cathode potential during normal tube operation. The screen mesh 20, which during tube operation will be several volts positive relative to target 22, provides a collector for secondary electrons which are emitted from the glass target 22 by the incident primary photoelectrons from the photocathode 14. It is understood that the specific voltages mentioned are only examples of those utilized in one successful form of my invention but that others could be used.

At the opposite end of the tubular envelope 10 there is positioned an electron gun structure comprising a thermionic cathode electrode 26 (Figure 2), a control grid 28, an accelerating electrode 30, and a limiting aperture electrode 32 all fixed to a tubular support member 24. The gun structure is described in greater details in my copending application Serial Number 9,420 filed February 19, 1948. This electron gun structure provides a beam of electrons which is formed into electron ray of small cross-section. The electron ray or beam is focused on the glass target 22 by an electrode 36, which may comprise a conductive coating on the inner wall of the tubular envelope portion 10. In the device shown the electrodes 30 and 32 are maintained positive during tube operation, for example, at close to 300 volts relative to the cathode electrode 26 to accelerate the electron beam to high velocity. As the electron beam leaves the limiting aperture 34 of electrode 32, the uniform axial magnetic field of coil 16 directs the beam substantially parallel to the axis of the tube. The beam 35 is caused to scan the surface of target 22 by two pairs of magnetic deflection coils represented by 40. Each pair of coils is arranged on an axis normal to the other. The fields of coils 40 are perpendicular to each other and to the axis of tube 10. Deflection coils 40 will have periodically varying voltages applied thereto, for example, by saw tooth generators (not shown) of suitable frequency, to produce line and frame scansion. Due to possible misalignment of the gun structure 24, relative to the tube axis, an alignment coil 39 is provided to maintain a small magnetic field perpendicular to the axis of the electron beam. Rotation of coil 39 around the stem of the tube envelope 10 will tend to correct any misalignment of the electron beam relative to the axis of the tube as it leaves the electron gun 24.

The wall coating electrode 36 during tube operation is maintained positive relative to the cathode potential, for example, at around 200 volts. Adjacent to the target 22 and between it and the focusing electrode 36 is a tubular electrode 38, which is maintained at close to cathode potential. Both the potential of the target 22 and of the cathode 26 are identical during tube operation. The beam in leaving the electron gun structure 24 is slowed down somewhat when passing into the lower potential field of electrode 36 and upon approaching target 22 is slowed down completely to essentially zero velocity by the decelerating fields of electrode

38 and of target 22. The low velocity beam 35 upon scanning the insulator surface of target 22 will lower the potential of the target to an equilibrium value of several volts negative relative to cathode potential, at which point the incident electron beam 35 will be turned back or reflected as a return beam 37. The secondary emission from the photocathode side of target 22 leaves on the surface of the glass target a charge pattern corresponding to the image of the scene focused on the photocathode 14.

The glass of target 22 has an electrical resistivity just low enough to permit a charge on one surface to unit by conduction in a frame time of about $1/30$ of a second with an opposite charge on the other surface. Also, the thickness of target 22 is small enough to prevent sideways spreading by conduction of these charges during a frame time. The close spacing of the target 22 from the fine mesh screen 20 increases the scene brightness of the charge image produced on the surface of target 22 by the photoelectrons from the photocathode 14. If no light falls upon the photocathode 14 glass target 22 will be charged to an equilibrium potential, negative relative to the cathode 26 by the incident scanning beam 35 as mentioned above. This equilibrium screen potential is a stable operating point, and is the potential the target 22 assumes in the absence of light and in the presence of the beam.

Photoelectrons from an illuminated spot on the photocathode 14 are guided in axial parallel paths by the magnetic field of coil 16 to the target 22. When the photoelectrons strike target 22 at an electron velocity of approximately 300 volts, they will eject a greater number of secondary electrons from a target area and leave the target area positively charged. The collecting potential of the fine mesh screen 20 is small and in the order of several volts positive relative to the equilibrium potential of target 22. Yet the collecting field of screen 22 is high because of its close spacing from target 22, so that the secondary electrons from the target 22 are almost completely collected by screen 20. The glass of target 22 is sufficiently thin, that each positive area formed on the photocathode side will attract incident electrons to a corresponding area on the beam side of the target. The low velocity scanning beam 35 will deposit sufficient electrons to neutralize the positive charges on the target 22, and to reduce the potential of each positive area of the target to the negative equilibrium target potential. During the following frame time, the positive and negative charges on the opposite sides of the glass target 22 unite by conduction. The neutralization of the charges on the two sides and the charging up by the photoelectrons are simultaneous as the scanning beam 35 passes over the positive areas of target 22, electrons are subtracted from the beam to neutralize or discharge these positive areas, as described above. The remaining portion of the beam is reflected from the discharged areas of the screen 22. Thus the return beam 37 is modulated by subtraction of electrons according to the positive charge pattern maintained on the glass target 22. The return beam is a maximum for regions of no light and a minimum for regions of high light areas.

Electrode 32 is the first stage of a multiplier section described in greater detail in Patent No. 2,433,941 of Paul K. Weimer, issued January 6,

1948. Electrode 32 is formed preferably from a silver magnesium sheet to provide a secondary electron emitting or dynode surface. The multiplier section also includes a second multiplier stage 44, a third multiplier stage 46, a fourth multiplier stage 48, and a fifth multiplier stage 52, each maintained during tube operation at progressively higher positive potentials. Secondary electrons from the dynode or first multiplier stage 32 will be collected in turn and amplified by secondary emission from successive stages 44, 46, 48, and 52. Electrode 50 is a collector maintained at a higher positive potential than the fifth multiplier stage 52 for collecting the resulting amplified secondary emission from the several multiplier stages.

The returning modulated beam strikes the first multiplier stage or dynode 32 to produce a secondary emission greater than that of the incident beam 37. Secondary electrons will be attracted to the second stage 44 maintained during tube operation positive relative to cathode potential at, for example, 600 volts. The secondary electrons strike the second stage surface 44 at velocities high enough to knock out more secondaries. These in turn pass on to the succeeding stages 46, 48, and 52, maintained at successively higher positive potentials and from which the electrons are collected by collector electrode 50 to form an amplified video signal of the tube. Multiplier stages 44, 46, and 48 each consist in this particular tube, of a thirty-two blade pinwheel, stamped from silver magnesium alloy. By forming the blades 45, 47 and 49 of the respectively consecutive pinwheels in an opposite sense, an opaque surface is seen by the approaching electrons while the secondary electrons are drawn through slots shown between the blades to the next succeeding stage. The three stages 44, 46, and 48 each respectively have a 90% transmission screen 51, 53, and 55. These screens 51, 53, and 55 each serve to prevent the relatively negative potential of the preceding stage from suppressing the collection of secondaries through the slots by the succeeding stage. The third stage 46 is maintained at approximately 880 volts, the fourth multiplier stage 48 is maintained at 1160 volts while the secondary emitting surface of the fifth stage 52 is maintained at 1450 volts. The collector electrode 50 comprises essentially an annular ring having a metal screen 57 stretched across its center. The collector electrode 50 is maintained during tube operation at approximately 1500 volts. All of these voltages are merely illustrative of those used in one tube made according to my invention.

The first multiplier stage 32 is located sufficiently outside of the focusing coil 16 that the magnetic field of this coil at this point is weak enough to allow secondaries to be drawn away from the first stage 32 and toward the second stage 44. To aid in this procedure, a persuader electrode 42 preferably maintained at slightly negative voltage relative to the voltage of the first stage 32 is arranged to enclose the dynode surface 32 of the first stage at one end thereof. The persuader electrode 42 not only prevents the secondary electrons emitted from surface 32 from impinging upon the glass wall 10 of the tube but also acts to provide a practically field free space above the surface of the dynode 32. Thus, the secondaries emitted from the surface 32 will tend to pass from the surface into the

field free space until they are "seen" by the field of the second stage 44.

The return beam scans across a small area of the surface of the first dynode 32 in a pattern corresponding to that scanned on the target electrode. The scanning of the first dynode surface is due to displacement of both the incident and the return beam caused by the crossed electrostatic and magnetic fields in the region of the decelerating electrode 38, as well as a helical motion retained by the return beam after its passage through the deflecting fields of coils 40.

In order for the second stage 44 to not introduce additional spurious signal, it must provide the same multiplication for electrons coming from each part of the first stage scanned by the return beam. If this requirement is not satisfied, the portion of the scanned area of the first stage whose secondaries are used less efficiently will appear in the transmitted picture as a lighter area of low signal. The term "multiplier shading" is used to refer to this effect regardless of whether it is caused by variation in secondary emission ratio of the first stage or by inefficient collection and multiplication of the secondaries from the first stage.

In trying to get the maximum possible total signal, it becomes increasingly difficult to get uniform collection, so that imperfections in collection that might not be so noticeable under lesser conditions are not more exaggerated. Such imperfections in collection might be due to a non-uniform field between the dynode surface 32 and the first stage multiplier electrode 44. The spurious signal, therefore, does not necessarily come from the addition of unwanted signal but rather is due at this stage to a subtractive effect resulting from an inability to collect with the same uniformity over the surface of the dynode 32. The returning electron beam 37 striking the dynode surface 32 produces a splatter of secondary electrons of varying velocities. At conditions of maximum collection, the lower velocity electrons are more susceptible to imperfections in the collecting field, which may either hinder or aid their collection selectivity over the dynode surface 32, and which introduces more severe shading problems.

The arrangement of a relatively flat dynode surface 32 enclosed within the field of the persuader electrode 42 is such that the secondaries produced at the surface of dynode 32 will first enter into a field free space before they enter the collecting field of the second stage 44. This improves the signal since it is only those electrons of higher velocity, and which comprise a truer reproduction of the signal, that will rise up into the collecting field of the second stage 44. Electrons of lower velocities and representing in a greater proportion the spurious signal will not be collected and will fall back and be suppressed by the field of the persuader electrode 42. In this manner of operation, the shading or spurious signal introduced by the multiplier is reduced until it is not objectionable. The voltage of the persuader electrode 42 is adjusted within several volts of that of the first stage 32 to give the most uniform shading.

One disadvantage of the symmetrical arrangement of multiplier electrodes 32, 42, and 44, around a common axis is that secondary electrons originating near the center of the dynode surface 32 may not be as completely collected by the field of the second stage 44 as are those secondaries

coming from points closer to the edge of dynode surface 32. This is due, not only to the fact that secondaries from the center must rise farther to enter the collecting field of electrode 44, but that the axial magnetic field of coil 16 encourages this situation. This problem is partially solved by locating dynode surface 32 within the relatively weak fringe field of solenoid 16.

Another disadvantage of the multiplier section was that the flat surface which was conventionally used for dynode 32 often was tilted at an angle to the multiplier axis during tube assembly. Only a very slight tilt was sufficient to produce non-uniform collection of secondaries from surface 32 by the second stage electrode 44. The tilt, which could not always be controlled in tube assembly, would be sufficient to result in a video signal producing a picture with a larger amount of shading on one side than the other. This was caused by the fact that the edge of the flat dynode surface 32 tilted toward the collector 44, exposed to a greater extent the areas of the dynode surface adjacent to the tilted edge to the strong field of collector 44. Also, areas of the dynode surface 32 on the opposite side were shielded to a greater extent from the field of collector 44 by the edge of dynode 32 tilted away from the collector 44. Thus lower velocity secondary electrons were collected from the areas of dynode surface 32 closer to the edge tilted toward collector 44 to produce uneven shading on the received picture.

To produce more uniform collection of secondary electrons from the center of dynode surface 32 and to eliminate the disadvantages of a tilted first stage dynode surface I have devised the first stage dynode electrode 32 shown in Figure 2. This electrode 32 is constructed with a spherical surface as is graphically indicated. This use of a spherical surface for the first stage eliminates the non-uniform collection of secondaries by the second stage 44. Any slight tilt of the spherical dynode surface 32 relative to the common axis of the multiplier would coincide with the spherical curvature of surface 32 so that there would be no tendency to raise one portion of surface 32 above another portion. Furthermore, the provision of a spherical surface keeps the center portion of the dynode surface 32 high so that there is eliminated any non-uniform collection of secondaries by the second stage 44 from this center area as described above. That is, with this structure the collecting field of the second stage 44 is more uniformly effective over all portions of the dynode surface 32.

The curvature of the dynode surface 32 is somewhat critical since it is possible to increase the spherical curvature of the surface to a point where all of the dynode surface 32 will be effectively "seen" by the collecting field of the second stage 44. As pointed out above, this is an undesirable condition since shading and spurious signal will result due to the collection by the second stage of an excessive amount of low velocity secondary electrons from the first stage. Thus, the spherical surface of dynode 32 is only of sufficient curvature to create more uniform collection of secondaries from the central portions thereof and to eliminate the defects of collection due to tilting of the dynode surface. In a particular tube similar to that shown in Figures 1 and 2 it has been found that the video signal of the tube has been greatly improved by using a dynode spherical surface having a radius of curvature of 5" and wherein the transverse section of the

dynode 32 is represented by an arc of approximately $\frac{3}{4}$ of an inch. Any spherical surface having greater curvature than this for this particular dynode surface results in greater shading and an increase in spurious signal. Any spherical surface for the dynode 32 which has smaller curvature will also operate, but the curvature improves the performance to give consistently good collection where many of the flat dynode surfaces will be found to result in undesirable shading in the transmitted picture. Tubes having a first stage surface of the dimensions described above, successfully use a second stage dynode wheel of approximately 1 $\frac{1}{2}$ " diameter.

While certain specific embodiments have been illustrated and described, it will be understood that various changes and modifications may be made therein without departing from the spirit and scope of the invention.

What I claim as new is:

1. An electron discharge device including a multiplier unit comprising a dynode plate having one face of a material which will emit secondary electrons when struck by primary electrons, and a collector plate electrode mounted opposite the other face of said dynode plate, said collector electrode extending beyond the periphery of said dynode plate, said dynode plate having a curvature away from said collector plate.

2. For use in a cathode ray discharge device, a multiplier unit comprising a dynode plate having a convex surface formed of a material providing secondary emission when struck by primary electrons of an electron discharge, and a collector plate electrode mounted coaxially to said dynode plate and mounted opposite the other side of said dynode plate, said collector plate extending radially beyond the periphery of said dynode plate.

3. For use in a cathode ray discharge device, a multiplier unit comprising a dynode plate having a convex surface, formed of a material providing secondary emission when struck by an electron discharge, an annular collector plate electrode coaxially spaced from the side of said dynode plate opposite to said convex surface, and a tubular member supporting said dynode plate and coaxially extending through said annular collector electrode, said annular plate extending radially beyond the periphery of said dynode plate.

4. For use in a cathode ray tube, a multiplier unit comprising a spherically shaped dynode plate, the convex surface of said dynode plate being of a material providing secondary emission when struck by primary electrons, and an annular collector plate coaxially mounted opposite the concave side of said spherical dynode plate and extending beyond the peripheral edge of said spherical dynode to collect the secondary emission from said convex surface.

5. An electron discharge device including a multiplier unit comprising a dynode plate having one surface which emits secondary electrons when struck by primary electrons, and a collector electrode mounted coaxially with said dynode plate and spaced from said secondary emitting surface symmetrically with respect thereto, said collector electrode positioned opposite the other surface of said dynode plate, said secondary emitting surface having a curvature away from said collector electrode.

6. A cathode ray discharge device comprising an evacuated envelope, a tubular electron gun structure mounted within said envelope for providing an electron beam along a path, a target

electrode within said envelope and mounted transversely to said electron beam path for returning part of said electron beam to said gun structure, and a multiplier unit including a spherically shaped plate fixed to one end of said gun structure, a tubular persuader electrode enclosing said plate, and a collector electrode spaced from said plate on the concave side thereof, said plate arranged with the convex surface thereof transverse to said electron beam path to intercept the return portion of said electron beam, said convex surface being of a material providing secondary emission when struck by the primary electrons of said return beam.

7. A television transmitting tube comprising an evacuated envelope, an electron gun including a tubular support member mounted within said envelope and a cathode electrode enclosed within said tubular support member for providing an electron beam along a path, a target electrode within said envelope transverse to the path of said electron beam for returning a part of said electron beam along said beam path, and a multiplier unit including a spherically shaped plate closing the end of said tubular member adjacent said target electrode, a tubular persuader electrode having one end enclosing said spherically shaped plate and a collector electrode spaced from said one end of said persuader electrode on the concave side of said plate, said plate having an aperture at the center thereof for the passage therethrough of electron emission from said cathode, said convex plate surface being of a material providing secondary emission when struck by the primary electrons of said return beam.

8. A cathode ray discharge device comprising an evacuated envelope, an electron gun structure within said envelope for producing an electron beam along a path including a cathode electrode and an apertured spherical plate spaced therefrom transversely along said beam path and arranged with the concave side of said plate facing said cathode electrode, a target electrode within said envelope transverse to said electron beam path for returning a part of said electron beam along said path, said spherical plate arranged between said cathode electrode and said target, the convex surface of said spherical plate being of a material providing secondary emission when struck by the primary electrons of said return beam, a multiplier unit including a persuader electrode mounted within said envelope between said spherical plate and said target electrode for

suppressing low velocity secondary electrons from said plate surface, and a collector electrode spaced from said persuader electrode on the concave side of said spherical plate.

- 5 9. A cathode ray discharge device comprising an evacuated envelope, an electron gun structure within said envelope for providing an electron beam along a path including a cathode electrode and a spherical dynode plate spaced from said cathode electrode and intercepting said electron path, said dynode plate having an aperture for masking said electron beam upon its passage therethrough and arranged with the concave side thereof facing said cathode electrode, a target electrode mounted within said envelope on the convex side of said dynode electrode for intercepting said electron beam and for returning a part of said electron beam back along said path, and a multiplier unit including a tubular 15 persuader electrode mounted between said dynode and said target electrodes and enclosing the convex surface of said dynode electrode for suppressing low velocity secondary electrons from said dynode plate and a collector electrode spaced 20 from said persuader electrode on the concave side of said dynode plate.

10. An electrode discharge device including a multiplier unit comprising a dynode plate having a convex spherical surface which emits secondary electrons when struck by primary electrons, and a collector electrode mounted coaxially with said dynode, said collector electrode mounted opposite the concave side of said convex dynode surface and symmetrically with respect thereto.

11. An electron discharge device including a multiplier unit comprising a dynode electrode having a convex spherical surface which emits secondary electrons when struck by primary electrons and a collector electrode for said secondary electrons mounted opposite the concave side of said convex surface and symmetrically spaced from the periphery thereof.
